HARRY J. BUTLER AND LOUIS P. CASPER, OF LOUISVILLE, KENTUCKY.

SPARK-PLUG.

1,116,238.

Specification of Letters Patent.

Patented Nov. 3, 1914.

Application filed November 4, 1912. Serial No. 729,459.

To all whom it may concern:

Be it known that we, HARRY J. BUTLER and LOUIS P. CASPER, citizens of the United States, and residents of Louisville, in the county of Jefferson and State of Kentucky, have invented a new and useful Improvement in Spark-Plugs, of which the following is a specification.

Our invention is an invention in spark 10 plugs for use with explosive engines or the like, and has for its object the provision of a plug of the character specified, wherein the electrodes or sparking points are so formed that deposits of carbon and the like 15 cannot accumulate on the points or electrodes, thus preventing the passage of the spark.

In the drawings:—Figure 1 is a vertical section of the improved plug on the line 20 1—1 of Fig. 2, Fig. 2 is a side view of the plug, Fig. 3 is a bottom plan view, Fig. 4 is a side view of the insulator, Fig. 5 is a side view of one of the electrodes, Fig. 6 shows two views at right angles to each 25 other of the vibrating or moving part that contacts with the electrodes, Fig. 7 is a view similar to Fig. 1 of a modified form of construction, Fig. 8 is a bottom plan view of Fig. 7, Fig. 9 is a side view of the insulating 30 member of the construction shown in Fig. 7, Fig. 10 is a side view of one of the electrodes of the said construction, and Fig. 11 is a plan view of the ball.

In the embodiment of the invention shown 35 in Figs. 1 to 6, the improved plug consists of a tubular nipple or holder 1, reduced and externally threaded at its lower end as shown at 2 for engaging an opening in the engine and internally threaded at its upper 40 end to receive a packing nut 3 for holding the insulator 4, the said insulator being of porcelain or other non-conducting material, having a central opening 5 for a purpose to be mentioned later, and having intermediate 45 its ends an annular enlargement 6, engaged by the packing nut 3 to hold the insulator in place in the holder 1.

A cylindrical nipple or extension 7 is provided at the upper end of the insulator 4, 50 and the lower end is recessed as shown at 8 to receive the movable member 9 shown in Fig. 6. It will be noted from an inspection of Fig. 4 that the recess 8 is longitudinal to the insulator 4, and that the lower end is 55 conical or trumpet-shaped, while at the up-

per end oppositely arranged bearing depressions 10 are provided for receiving the trunnions 11 of the movable member 9. The member 9 is thus mounted for swinging movement in the recess 8, swinging on the 60 trunnions 11, and the lower bulbous portion 12 of the movable member extends below the lower end of the insulator 4 and is adapted to engage alternately the adjacent ends of the electrodes.

One of the electrodes 13 is in the form of a rod having its upper end threaded and having at its lower end an enlarged elbow 14. The body of the electrode 13 passes through the opening 5 of the insulator, the 70 elbow 14 being below the lower end of the insulator. A shoulder 15 is formed at the junction between the elbow and the body of the electrode for engaging the lower end of the insulator to limit the upward movement 75 of the electrode. The upper end of the electrode extends above the nipple 7, and nuts 16 and 17 are threaded on to the electrode above the insulator. The usual ring 18 connected with the end of the cable or conductor that leads from the magneto or battery to the spark plug encircles the electrode 13 between the nuts 16 and 17, and the nut 16 is provided in its lower end with a recess 80 for receiving the nipple 7. The other electrode 19 is of usual form, being in the shape of an elbow extending longitudinally from the lower end of the holder 1.

In operation, the current passes from the magneto or battery through the electrode 13 90 and the elbow 14 to the electrode 19 and through the engine to the ground. The bulbous portion 12 of the movable member 9 is between the adjacent ends of the elbows 14 and 19 and the said member is free to 95 swing from one of the electrodes to the other. When the bulbous portion 12 is out of contact with either electrode, a double spark is formed, while when the said member is in contact with the elbow 19 100 the spark passes from the elbow 14 to the said member and to the electrode 19. When the movable member is in contact with the elbow 14 the spark is between the bulbous portion 12 of the member 9 and the electrode 19. The said member 9 is free to 105 swing as before stated between the electrodes and the said member will prevent any fouling or deposit of carbon on the points of the electrodes.

In the constructions shown in Figs. 7 to 11, the holder 20 is in all respects the same as the holder 1, having the reduced external threaded portion 21 for engaging the opening of the engine and being internally threaded at its upper end to receive the packing nut 22. The insulator 23 is provided with an annular enlargement or rib 24 intermediate its ends, and it will be noticed that in both constructions the upper ends of the holder 1 and 20 are enlarged annularly to form an annular shoulder against which the lower face of the rib 24 may rest.

15 The packing nut 22 engages above the rib 24 to hold the insulator in place and the upper end of the insulator is provided with the cylindrical nipple 25, corresponding to the nipple 7. One of the electrodes is in 20 the form of a rod 26 having at its lower end a head 27, and the rod passes through a longitudinal opening in the insulator, the head limiting the upward movement of the electrode. Packing nuts 28 and 29 are 25 threaded on to the upper end of the rod and the ring 30 of the conducting cable is held between the said nuts. The lower end of the nut 28 is recessed longitudinally to receive the nipple 25.

30 The electrode connected with the holder 20 is in the form of an elbow 31, and the head 27 and the inner free end of the elbow 31 are directly opposite each other. The lower end of the insulator is provided with 35 a transverse circular opening, as shown at 32 in Fig. 9, and the head 27 is at one side of the said opening extending into the same, while the elbow 31 extends into the opposite side. A ball 33 of conducting material 40 (Fig. 11) is arranged between the lower end of the two electrodes, the said ball being freely movable in the opening 22 between the head and the elbow.

45 In the construction of Figs. 7 to 11 the ball 33 acts in the same manner as the

bulbous portion 12 of the member 9 and the same result is attained.

We claim:

1. A spark plug comprising a tubular holder, having means for engaging an engine, an insulator of approximately cylindrical form in the holder, means for connecting the insulator to the holder, said insulator having a longitudinal opening, an electrode in the opening and extending beyond the insulator at both ends, the lower end of the electrode having an angular lug and the holder having a lug opposite the lug of the electrode, and a member of conducting material supported by the insulator between the lugs and freely movable with respect thereto.

2. A spark plug comprising a holder, an electrode extending longitudinally of the holder, an insulator between the electrode and the holder, said insulator having a recess extending transversely between the electrode and the holder, and a movable member of conducting material within the recess and supported by the insulator and movable freely between the electrodes, whereby to contact with either electrode.

3. A spark plug having laterally spaced electrodes, the terminals of the said electrodes being spaced apart laterally from each other, and a member of conducting material supported between the terminals and mounted for free lateral movement between the said terminals.

4. A spark plug having electrodes whose terminals are spaced apart laterally from each other, and a movable member supported between the electrodes and mounted for free lateral movement to contact with either electrode.

HARRY J. BUTLER.
